UNITED STATES PATENT OFFICE.

HARRY C. SILLETT, OF SALT LAKE CITY, UTAH.

DEEP-WELL CABLE-PUMP.

No. 892,093.

Specification of Letters Patent.

Patented June 30, 1908.

Application filed June 25, 1906. Serial No. 323,327.

To all whom it may concern:

Be it known that I, HARRY C. SILLETT, a citizen of the United States, residing at Salt Lake City, in the county of Salt Lake and State of Utah, have invented a new and useful Improvement in Deep-Well Cable-Pumps, of which the following is a specification.

This invention relates to pumps and more particularly to deep well cable pumps, the object being to provide a pump which will hoist the water from deep wells instead of pumping it.

Another object of my invention is to provide a pump which will be capable of delivering a greater amount of water than any of the pumps now in use, at about one half the cost of operating.

Another object of my invention is to provide a pump so constructed that the cost of repair is greatly reduced as the wooden poles and the leather cups are done away with, as the said parts have to be pulled to the surface to be repaired, which require a great deal of labor and expense as each of the rods has to be disconnected as it reaches the top of the well.

With these objects in view, the invention consists in the novel features of construction, hereinafter fully described and pointed out in the claims.

In the drawings forming a part of this specification Figure 1 is a vertical sectional view of a well showing my improved pump arranged therein. Fig. 2 is a vertical sectional view partly in elevation of the head. Fig. 3 is a top plan view of the casting and sheaves for guiding the cable, and Fig. 4 is a side view partly in section of the plunger.

In the drawing A indicates a well casing which is secured in the usual manner and in which pump tubing B is supported by means of clamping strips C secured to said tubing and adapted to rest across the top of the well. The upper end of the tubing extends upward through a platform D and is provided with a flange B' and to this flange B' is secured the lower end E' of the head E. This head is also provided with a flanged discharge pipe E² to which is secured a pipe E⁴ by means of which the water can be carried off to any point desired. A tube F having a flange F' at its lower end is bolted to the upper end E³ of the pump head and upon the upper end of this tube F is fitted a casting F² on which are arranged the sheave brackets F³ and in which are mounted the grooved sheaves or

pulleys G forming a guide for the steel cable H which is adapted to be wound upon a drum of an ordinary hoisting engine for the purpose of lifting the plunger and consequently raising the water. A sinker bar I of any desired weight is secured to the end of the cable H and carries a rod J at its lower end and upon this rod J are arranged a series of flanged disks J' having rings J² of hard packing material arranged between the disks all of said parts being secured by means of nuts thereby providing a plunger which is adapted to work up and down in the pump tube and lift the water, it being understood that the water enters the tubing after the plunger has been lowered and as the plunger is raised by means of the cable a volume of water is lifted equal to the amount of water standing in the tubing above the plunger when the said plunger starts upwardly. A pipe K is tapped into the tubing F above the pump head and extends downwardly into the well casing, connects with the tubing at a point adjacent the suction limit and this pipe is preferably provided with a valve K' by means of which said pipe can be opened or closed. The water passing across the lower end of the pipe K creates a suction in said pipe and through the tube F and the circulation of this air will serve to dry the cable as it passes through the tube F and will prevent water being thrown from said cable as it is wound upon the winding drum and this air pipe K also prevents the formation of a vacuum in the well tubing. It will be understood that whenever the well casing is large enough two tubes will be arranged therein each carrying a plunger and the cables so arranged that as one plunger is being lifted the other one will be lowered and in this manner a continuous stream of water will be lifted.

Having thus fully described my invention, what I claim as new and desire to secure by Letters Patent is:—

1. In a pump of the kind described a combination with a pump tube provided with a head, a discharge pipe connected to the head, a plunger operating in the pump tube and a cable for lifting said plunger, a tube fastened to the pump head and carrying a cable guide at its upper end and the air pipe extending from said tube into the pump tubing at a point adjacent the suction limit.

2. In a device of the kind described the combination with a casing, of the tubing ar-

ranged therein, a pump head arranged upon the upper end of the tubing and provided with a discharge pipe, the plunger working in the pump tubing, a cable for raising the same, the tube attached to the upper end of the pump head and carrying cable guides at its upper end, the air pipe connected to said tube at a point above the pump head, the

lower end of said pipe entering the pump tubing at the suction limit, and a valve arranged in said pipe intermediate its ends for the purpose set forth.

HARRY C. SILLETT.
